UNITED STATES PATENT OFFICE.

JOHN T. WILSON, OF PITTSBURG, PENNSYLVANIA.

CAR-COUPING.

SPECIFICATION forming part of Letters Patent No. 632,302, dated September 5, 1899.

Application filed May 20, 1899. Serial No. 717,593. (No model.)

To all whom it may concern:

Be it known that I, JOHN T. WILSON, a citizen of the United States, residing at Pittsburgh, in the county of Allegheny and State of Pennsylvania, have invented certain new and useful Improvements in Car-Couplings; and I do hereby declare the following to be a full, clear, and exact description of the invention, such as will enable others skilled in the art to

10 which it appertains to make and use the same.

My invention relates to car-couplings, has especial reference to that class known among railroad men as the "Janney type" or the "Master Car-Builders' couplings," and has for 15 its object certain improvements in construction of the pin to prevent accidental uncoupling by the "jumping" or "creeping" out of engagement with the tongue or tailpiece of the hook by jolts or jars or the gradual raising 20 of the pin by the tongue; and it consists in certain constructions of the draw-head and the pin, which will be fully disclosed in the following specification and claims.

In the accompanying drawings, which form 25 part of this specification, Figure 1 represents a side elevation of a draw-bar, illustrating the application of my invention, with the hook or jaw open and the pin raised, with its notch or recess in position for the tongue of the hook to 30 pass the pin; Fig. 2, a like view showing the hook closed and the tongue locked by the pin; Fig. 3, an enlarged detail of the pin, and Fig. 4 a like view of a modified form of the pin.

Reference being had to the drawings and 35 the letters thereon, A indicates the head of a draw-bar, B the body or shank, C the hook or jaw, all of which may be of any approved pattern, and D the pin or latch, which with its coacting parts constitute the vital part of 40 my present invention.

The gravity pins or latches for this class of 45 couplings as usually constructed frequently become displaced by a sudden jolt or jar, or they rise gradually and imperceptibly by the motion of the tongue and its pressure against the pin, producing what is known among trainmen as "creeping" of the pin and by which the pin finally rises high enough to release the hook and sever the couplings between 50 two cars. To overcome this serious defect, the pin D is provided with a laterally-projecting stud a or a continuous spiral lateral projection b, which engages a vertically-inclined groove c in a boss or vertical extension d on the upper side of the body of the

draw-bar, and with a lever e, by which the pin is raised and lowered by the trainmen to couple and uncouple a train. The pin is also provided with a groove f, through which the end of the tongue g of the hook or jaw passes 60 as the hook engages with the hook of the coupling on an adjacent car, and the pin is supported by a collar h, resting on the upper surface of the boss d when the pin is down. After the coupling has been made the pin D 65 is lowered, the groove f being turned on the rear or opposite side from the mouth of the draw-bar, as shown in Fig. 2.

The pin has two motions imparted to it as it is raised and lowered—namely, vertical and 70 axial or rotary—the latter being equal to one-half of a revolution to present the groove f in line for the tongue of the hook to pass through it in the upstroke and to restore or return the groove to its normal position in the down- 75 stroke.

The stud a or the projection b on the pin D produces sufficient resistance in the groove c to prevent the pin jumping or creeping, and thereby accidentally uncoupling a train while 80 in motion.

Having thus fully described my invention, what I claim is—

1. In a car-coupling, the combination of a laterally-swinging hook, a pin engaged by the 85 tongue of the hook and having a groove normally on the rear side thereof for the passage of the tongue, and means for effecting vertical and axial or rotary movements of the pin to couple and uncouple. 90

2. In a coupling, the combination of a laterally-swinging hook, a pin vertically and axially movable and engaged by the tongue of the hook and having a lateral projection on the body thereof, and a vertically-inclined 95 groove in the draw-bar engaged by the projection on the pin.

3. In a car-coupling, the combination of a laterally-swinging hook, a pin engaged by the tongue of the hook and movable vertically 100 and on its axis and provided with a lateral projection on the body thereof, and a spiral groove in the draw-bar engaged by the projection on the pin.

In testimony whereof I affix my signature 105 in presence of two witnesses.

JOHN T. WILSON.
